UNITED STATES PATENT OFFICE.

PAUL ANDERSEN, OF FREEPORT, NEW YORK.

DESIGN FOR A HAMMER-HEAD.

44,649.

Specification for Design.

Patented Sept. 16, 1913.

Application filed July 9, 1913. Serial No. 778,223. Term of patent 7 years.

To all whom it may concern:

Be it known that I, PAUL ANDERSEN, a citizen of the United States, and a resident of Freeport, in the county of Nassau and State of New York, have invented a new, original, and ornamental Design for Hammer-Heads, of which the following is a specification, reference being had to the accompanying drawing, forming part thereof.

The figure is a perspective showing my new design.

I claim:

The ornamental design for a hammer head, as shown.

PAUL ANDERSEN.

Witnesses:

CHATTIN BRODWAY,
PHILIP D. ROLLHAUS.
